F. X. MALOCSAY

CIGAR BANDING MACHINE

Filed July 26, 1923

Francis X. Maloney, INVENTOR
S. Schuchert & Kotacek, BY
his ATTORNEY.

UNITED STATES PATENT OFFICE.

FRANCIS X. MALOCSSAY, OF UPPER SADDLE RIVER, NEW JERSEY, ASSIGNOR TO INTERNATIONAL BANDING MACHINE COMPANY, A CORPORATION OF NEW YORK.

CIGAR-BANDING MACHINE.

Application filed July 26, 1923. Serial No. 653,830.

This invention relates to cigar banding machines, and is an improvement on the machine shown in my copending application, Serial No. 483,464, filed July 9, 1921. In 5 the machine of said application, there is provided a reciprocatory carriage over which is adapted to be fed a gum tape, moistened at a suitable point in its passage around said carriage. Said carriage and tape are operated 10 toward a band stack which is moved upwardly into engagement with the gum tape. Said gum tape carries therewith the outermost band which adheres thereto and positions said band in the path of the band wrapping 15 fingers. During the movement of the carriage in one direction, the gum tape which is looped around the carriage is adapted to be gripped at one point so that the other loop must move forwardly to unwind from 20 a supply roll. On the return movement, the upper branch of the loop is released so that both branches of the loop move back simultaneously. In this manner the upper branch gains continuously at each reciprocation 25 of the carriage. As hereinbefore stated, the tape is adapted to be moistened at a certain point in its passage around the carriage and at a certain distance in advance of the band stack. It has been found that the portion 30 of the tape in effective position to engage the band stack was frequently either too moist or too dry, depending upon the condition of the atmosphere. Thus, in wet weather, the portion of the tape in effective position was 35 found to be too moist and the gum inclined to run, while in dry weather the gum was found to be of too great a consistency, resulting in poor application of the gum to the cigar band and hence liability of said bands 40 to unwrap from the cigar.

It is one of the objects of my present invention to overcome and eliminate the objections hereinbefore mentioned. Therefore, I provide an adjustment on the said tape feeding means whereby the tape may be delivered 45 to effective position to engage the band stack with the gum thereon always of the same desired consistency, regardless of the moisture contained in the atmosphere. For this purpose I provide means for increasing or decreasing the rate of movement of said tape, that is, for increasing or decreasing the amount that said tape advances at each step corresponding to each reciprocation of the carriage. So that, in wet weather, a slower 50 feeding of the tape may be obtained, while in dry weather a more rapid feeding may be obtained.

It is a further object of this invention to accomplish the above results by a device 55 which is extremely simple and which involves a minimum of change of the machine illustrated in said copending application, Ser. No. 483,464, so that this invention may be readily applied to said machine with a 60 minimum of expense and effort.

Other objects and advantages will appear as the nature of the improvements is better understood, the invention consisting substantially in the novel arrangement and correlation of instrumentalities herein fully described and illustrated in the accompanying drawings, wherein similar reference characters are used to describe the corresponding parts throughout the several views, 70 and then finally pointed out and specifically defined and indicated in the appended claims.

The disclosure made the basis of exemplifying the present inventive concept suggests 75 a practical embodiment thereof, but the invention is not to be restricted to the exact details of this disclosure, and the latter, therefore, is to be understood from an illustrative, rather than a restrictive, standpoint.

The inventive idea involved is capable of receiving a variety of mechanical expressions, one of which, for the purposes of illustration, is shown in the accompanying drawings, in which— 80

Fig. 1 is a vertical side section through a portion of a cigar banding machine, all parts of said machine except those cooperating directly with my invention having 85 been omitted, and my invention being shown applied thereto.

Fig. 2 is a partial, vertical section through the gripping finger and actuating member therefor, taken on the line 2—2 of Fig. 1.

Fig. 3 is a view similar to Fig. 2, but with 90 the parts in a different operative position.

Referring to the drawings, there is shown a carriage 10 adapted to be reciprocated in a forwardly and rearwardly direction (here shown as left and right) by mechanism not 95 shown but fully described in my said copending application. Over said carriage is adapted to operate a gum tape 12, said tape issuing from a fixed guide 15 passing over a guide roller 16 and a moistening roller 17,

which operates in a reservoir 18. The tape is pressed against said roller by a pressure roller 20, and then passes around the nose 21 of said carriage, which is provided with a flat portion 22, adapted to engage the band stack 23. The tape then passes around the carriage to the upper side thereof and returns over said fixed guide. The lower branch 25 of the tape is adapted to unwind from a supply roll (not shown) back of the fixed guide. In Fig. 1 the carriage is shown in its forward effective position over the band stack, which at the same time is moved upwardly into engagement with the portion 15 of the tape beneath the flat nose 22, so that, when the carriage is reciprocated to the right, it carries the uppermost band to banding position.

With each reciprocation of the carriage, it is desired to feed a fresh portion of the tape to effective position beneath the flat nose 22. This is accomplished by means of a gripping finger 30, normally spring-pressed downwardly into engagement with the upper branch 26 of the tape by means of a spring 31 engaging a fixed bracket 32 and said finger. Said finger is adapted to be lowered to clamp the tape against the fixed guide just before the carriage begins its movement toward effective position (in this case to the left), so that as the carriage advances, it is necessary for the bottom branch 25 of the tape to give, since the upper branch is held fixed. By the time the carriage has reached effective position over the band stack, therefore, the bottom branch 25 has been advanced around the nose 21, the upper branch 26 thus gaining a piece of tape, substantially the same amount having been unwound from the supply roll. On the return movement of the carriage, the finger 30 is adapted to be lifted out of gripping engagement with the tape, so that both branches of the tape draw back by gravity. The upper branch 26 has therefore gained a certain amount of tape, and a certain amount of new tape has been added to the lower branch from the supply roll. As hereinbefore stated, the gripping finger 30 is adapted to grip the upper branch 26 of the tape against the fixed guide by means of the spring 31. To render the finger ineffective, there is provided a stem 35 engaging at one end in a socket 36 fixed to the finger and at the other end one arm of a bell crank 37, the other arm of which is in engagement with a cam 38. When the carriage is about to move to effective position, the cam 38 permits rod 35 to drop and hence permits spring 31 to move gripping finger 30 into engagement with the tape, but on the return movement of the carriage, the cam raises the rod 35 to lift the finger 30 out of engagement with said tape.

As fully set forth in the introduction to

this specification, it is desirable frequently to adjust the rate of feeding of the gum tape to effective position beneath nose 22. For this purpose I vary the amount of movement of said tape at each reciprocation of the carriage by varying the length of time that the gripping finger 30 clamps the upper branch 26 of the tape to the fixed part of the machine. It is obvious that if the rod 35 engages the socket 36 to lift the finger 30 when the carriage has moved only half way toward effective position, only half as much tape will be fed around the nose of the carriage as when said finger 30 is permitted to clamp the upper branch of the tape throughout the entire movement of the carriage to effective position, for it will be understood that once the gripping finger 30 is raised, both branches of the tape are carried together without any movement around the nose of the carriage. To permit varying the point at which said finger is raised to release the upper branch of the tape, I provide said hollow socket 36 on said finger, into which is threaded a nut 40 with the lower end of which is adapted to engage the upper end of rod 35. When the rod 35 is in its lowered position to permit finger 30 to engage the tape, there is a certain amount of lost motion between said upper end of rod 35 and the lower end of nut 40. The cam 38 is so formed that rod 35 begins to move upwardly substantially at the same time that the carriage moves toward effective position. The length of time that the gripping finger will engage the upper branch 26 of the tape is, therefore, directly proportional to the amount of lost motion between the upper end of rod 35 and the lower end of nut 40. Obviously, then, if this amount of lost motion is varied, the length of time that said upper branch of the loop is clamped against movement will be correspondingly varied. The nut 40 may be threaded upwardly or downwardly to increase or decrease respectively the length of time that said gripping finger clamps the tape. The lower end of bolt 40 may be provided with a socket 41 in which the upper end of rod 35 may seat, while said rod is raising the finger, as shown in Fig. 2. Since the socket 36 is tilted in its ineffective position relative to rod 35, which is always substantially vertical, the lower end of the socket is provided internally with a flaring portion 42 to permit the upper end of rod 35 to play freely in said socket.

In accordance with the provisions of the patent statutes, I have described the principle of my invention together with the apparatus which I now consider to represent a practical embodiment thereof, but I desire it understood that my invention is not confined to the particular form of apparatus herein shown and described, the same being merely illustrative; and that the invention

can be carried out in other ways without departing from the spirit of my invention, and, therefore, I claim broadly the right to employ all equivalent instrumentalities coming within the scope of the appended claims, and by means of which the objects of my invention are attained, and the new results accomplished, as herein set forth, as it is obvious that the particular embodiments herein shown and described are only some of many that can be employed to attain these objects and accomplish these results.

Having described my invention, what I claim and desire to secure by Letter Patent is:

1. In a device of the character described, a tape, a carriage for said tape adapted to be reciprocated between effective and ineffective positions, means whereby the movement of said carriage feeds said tape, and means for varying the rate of feed.

2. In a device of the character described, a tape, a carriage for said tape adapted to be reciprocated between effective and ineffective positions, means whereby the movement of said carriage toward effective position feeds said tape, and means for varying the rate of feed.

3. In a device of the character described, a carriage adapted to be reciprocated between effective and ineffective positions, a tape looped around said carriage, means adapted to engage one branch of the loop during movement of said carriage so that the tape is fed around said carriage from the other branch, and means for varying the period of engagement of said first means with said tape.

4. In a device of the character described, a carriage adapted to be reciprocated between effective and ineffective positions, a tape looped around said carriage, means adapted to engage one branch of the loop during movement of said carriage toward effective position so that the tape is fed around said carriage from the other branch, and means for varying the period of engagement of said first means with said tape.

5. In a device of the character described, a carriage adapted to be reciprocated between effective and ineffective positions, a tape looped around said carriage, means adapted to engage one branch of the loop during movement of said carriage so that the tape is fed around said carriage from the other branch, means for rendering said first named means ineffective, and means for varying the time at which said last named means actuates said first named means.

6. In a device of the character described, a carriage adapted to be reciprocated between effective and ineffective positions, a tape looped around said carriage, means adapted to engage one branch of the loop during movement of said carriage so that the tape

is fed around said carriage from the other branch, means normally rendering said first named means effective, means for rendering said first named means ineffective, and means for varying the time at which said last named means actuates said first named means.

7. In a device of the character described, a carriage adapted to be reciprocated between effective and ineffective positions, a tape looped around said carriage, means adapted to engage one branch of the loop during movement of said carriage so that the tape is fed around said carriage from the other branch, means for rendering said first named means ineffective, and means for varying the time at which said last named means actuates said first named means, said last named means including a lost motion connection.

8. In a device of the character described, a carriage adapted to be reciprocated between effective and ineffective positions, a tape looped around said carriage, means adapted to engage one branch of the loop during movement of said carriage so that the tape is fed around said carriage from the other branch, means for rendering said first named means ineffective, means for varying the time at which said last named means actuates said first named means, said last named means including a lost motion connection, and means for varying the degree of lost motion.

9. In a device of the character described, a carriage adapted to be reciprocated between effective and ineffective positions, a tape looped around said carriage, means adapted to engage one branch of the loop during movement of said carriage so that the tape is fed around said carriage from the other branch, and means for rendering said first named means ineffective at a predetermined time during the movement of said carriage.

10. In a device of the character described, a carriage adapted to be reciprocated between effective and ineffective positions, a tape looped around said carriage, a gripping member adapted to engage one branch of the loop during movement of said carriage toward effective position so that the tape is fed around said carriage from the other branch, and means for rendering said gripping member ineffective at a predetermined time during the movement of said carriage.

11. In a device of the character described, a carriage adapted to be reciprocated between effective and ineffective positions, a tape looped around said carriage, a gripping member adapted to engage one branch of the loop during movement of said carriage toward effective position so that the tape is fed around said carriage from the other branch.

other branch; means for rendering said gripping member ineffective at a predetermined time during the movement of said carriage, said means comprising an actuating member, and an adjustable lost motion connection between said gripping member and said member.

12. In a device of the character described, a carriage adapted to be reciprocated between effective and ineffective positions, a tape looped around said carriage, a gripping member adapted to engage one branch of the loop during movement of said carriage toward effective position so that the tape is fed around said carriage from the other branch, means for rendering said gripping member ineffective at a predetermined time during the movement of said carriage, said means comprising an actuating member, a lost motion connection between said gripping member and said member, and means for adjusting the degree of lost motion.

13. In a device of the character described, a carriage adapted to be reciprocated between effective and ineffective positions, a tape looped around said carriage, a gripping finger adapted to engage one branch of the loop during movement of said car-

riage toward effective position so that the tape is fed around said carriage from the other branch, means for rendering said finger ineffective at a predetermined time during the movement of said carriage, said means comprising a socket carried by said finger, an actuating member engageable in said socket, and an adjustable lost-motion connection between said member and said socket.

14. In a device of the character described, a carriage adapted to be reciprocated between effective and ineffective positions, a tape looped around said carriage, a gripping finger adapted to engage one branch of the loop during movement of said carriage toward effective position so that the tape is fed around said carriage from the other branch, means for rendering said finger ineffective at a predetermined time during the movement of said carriage, said means comprising a socket carried by said finger, a bolt threaded in said socket, an actuating member engageable with said bolt, and means for adjusting the position of said bolt relative to said means.

This specification signed this 24th day of July, 1923.

FRANCIS X. MALOCSSAY.
